Patented Dec. 3, 1918.

FIG. 1

FIG. 2

FIG. 3

Inventor,
Zack G. Oldham;

By Raymond S. Kellee,
His Attorney.

UNITED STATES PATENT OFFICE.

ZACK G. OLDFHAM, OF LOS ANGELES, CALIFORNIA.

BOXING-GLOVE.

1,286,396.

Specification of Letters Patent.

Patented Dec. 3, 1918.

Application filed April 29, 1918. Serial No. 231,298.

To all whom it may concern:

Be it known that I, ZACK G. OLDFHAM, a citizen of the United States, residing at Los Angeles, in the county of Los Angeles and State of California, have invented new and useful Improvements in Boxing-Gloves, of which the following is a specification.

This invention relates to boxing gloves, and has for its object to provide an improved boxing glove which will be superior in point of relative simplicity and inexpensiveness of construction and organization, taken in conjunction with extended life and increased durability, increased resilience or elasticity as to the cushioning element or elements thereof, which will provide more effectively for maintaining the cushioning elements thereof in even distribution and disposition, and which will be generally superior in efficiency and serviceability and convenience in assembling or repair of parts.

With the above and other objects in view, the invention consists in the novel and useful provision, formation, construction, combination, association and inter-relation of parts, members and features, all as herein-after described, shown in the drawing, and finally pointed out in claims.

In the drawing:

Figure 1 is an inner face view of a boxing glove constructed and organized in accordance with the invention;

Fig. 2 is a rear face view of the same, parts being broken away for clearness of illustration; and

Fig. 3 is a detail transverse sectional view of the same, taken upon the line x^3-x^3 , Fig. 1.

Corresponding parts in all the figures are designated by the same reference characters.

Referring with particularity to the drawing, the improved boxing glove comprising the invention, comprises, in combination or association with a front or inner body wall 4, a rear or outer body wall 5, and a palm-covering member 6; of a filling or padding or cushioning member or element 7 disposed between the walls 4 and 5, such member or element extending both into the thumb portion B, and into the hand portion A of the glove. The glove is provided with a wrist portion C built up of the inner body wall 4 and the palm covering member 6, and a wrist band 8 joined with the side edges of both of the same, as at 8^a, and with the end edge of the inner body wall 4, and extend-

ing around the back of the wrist of the wearer below the terminal portion of the outer body wall 5, to which it may be laced, as at 9, after the filling or padding member 6 or element 7 has been introduced into the space between the inner body wall 4 and the outer body wall 5. This lacing thus retains the filling in place. This filling member 7, in accordance with the invention, comprises sponge rubber or porous rubber throughout the mass of which are freely distributed voids, such material being commonly known as sponge rubber.

A suitable lacing 10 is applied to the palm 70 covering 6, in the wrist portion C of the glove, so as to draw the wrist portion together over the wrist of the wearer and hold the glove in place. The usual suitable holes 11 are provided in the palm covering 6, for 75 ventilation of the space between the palm covering and the inner body wall 4, to suitably air the hand when in the glove. The wrist band 8 may or may not be otherwise attached or stitched to the front body wall 80 4, as by lines of stitching 12, in accordance with preference or expediency.

It will be readily understood from the foregoing description and the accompanying drawing, that the general make-up of the 85 boxing glove as to its body walls, palm covering, wrist portion and lacing 12 at the wrist portion, is in accordance generally with standard practice. The invention particularly relates to the nature and organization of the filling, or padding or resilient element 7 disposed between the inner body wall 4 and the outer body wall 5. This material, which, either in one mass or in two masses, or a greater number of masses if desired, is introduced into the space mentioned is of such a resilient and durable quality, and is so evenly distributed, and so effectively maintains its even distribution, that the padding or filling of the glove has 90 extremely beneficial and greatly improved qualities. In the first place, the glove is given that quality of resilience which renders it much safer in use and much less liable to produce injury or discomfort upon 100 impact against the face or person of an adversary, protecting such adversary against inadvertent or accidental blows which otherwise might cause inconvenience, damage, and as sometimes occurs, extreme injury and discomfort. Particularly do these qualities appeal to amateur boxers, who desire more to 105 110

score tactical or strategetic points, than to do physical violence to each other. However, the blow of the glove is not robbed of all of its salutary and health-giving effects, nor of those aggressive results which, among sturdy and healthy contestants, are relished rather than feared or avoided. Furthermore, the inherent tendency of the filling element 7 to maintain its even distribution, prevents the filling from becoming bunched or misplaced or unevenly distributed, so that it results that the knuckles or other portions of the hand are not inadvertently, and cannot even intentionally, be bared to produce more strenuous and damaging blows than expected from the hand properly covered by a boxing glove. In the use of gloves as ordinarily organized in standard practice, the padding or filling may readily be shifted or displaced, being of a loose and easily separated or subdivided or shifted nature or character, and this permits the user to unfairly vary the striking quality of his glove so as to take advantage of his adversary. This is often met with in the conducting of boxing bouts, namely, the unfair disarrangement of the padding or filling of the glove, so as to take advantage of the adversary, and in the use of the padding or filling element 7 this is well nigh impossible, and even were the padding or filling shifted or separated, it would tend to re-assume its former position in complete occupation of the filling-retaining space.

35 In practice it has been found that this filling or padding element 7 is many times as durable as, and has several times the life of, the padding or filling ordinarily found in boxing gloves; and it is found to reliably keep its form and distribution, and to lend a quality to the blow of the glove which is pleasing and unharful and at the same time has all of the life and vigor of impact which is relished in this pastime.

40 As to length of life, it has been found that this padding or filling will outwear several glove bodies, the life of the filling being for practical purposes, without limit. The lacing connection at 9 permits of convenient introduction of the padding element 7, to the accommodating space in the body of the glove, and likewise permits of convenient withdrawal of such padding element for replacement or any other purpose if required, or for removal to introduce within a fresh or a new glove body.

It is manifest that changes and modifi-

cations and variations may be made as to the construction and organization of the boxing glove, including the general elements of body structure, and the like, and the specific nature of the filling or padding or resiliency element 7, all in contradistinction from the foregoing description and statement, and the accompanying drawing, without departing from the spirit of the invention and the terms of the following claims.

Having thus disclosed my invention, I claim and desire to secure by Letters Patent:

1. A boxing glove having a body provided with a space for receiving and confining a padding or filling, and a padding or filling element in such space and comprising a sponge rubber mass.

2. A boxing glove having body members providing a space for receiving and confining a padding or filling, and a padding or filling element in such space and comprising a sponge rubber mass.

3. A boxing glove having body members providing a space for receiving and confining a padding or filling, and a padding or filling element in such space and comprising a rubber mass containing voids; said glove having a hand portion and a thumb portion throughout both of which said rubber mass is distributed.

4. A boxing glove having body members providing a space for receiving and confining a padding or filling, and a padding or filling element in such space and comprising a rubber mass containing voids; said glove being provided with a wrist portion and with an opening at the wrist portion through which said rubber mass may be introduced; and means for closing said opening.

5. A boxing glove having body members providing a space for receiving and confining a padding or filling, and a padding or filling element in such space and comprising a rubber mass containing voids; said glove being provided with a wrist portion and with an opening at the wrist portion through which said rubber mass may be introduced; and lacing for closing said opening.

In testimony whereof, I have signed my name to this specification in the presence of two subscribing witnesses.

ZACK G. OLDHAM.
